Primary Examiner — Jack Reickel*Assistant Examiner* — Rachel A Voorhies(74) Attorney, Agent, or Firm — Finnegan, Henderson, Farabow, Garrett & Dunner LLP(57) CLAIM

The ornamental design for a display screen with icon, as shown and described.

DESCRIPTION

The sole FIGURE is a front elevation view of a display screen with icon, showing the new design.

The broken lines of uneven length illustrate a display screen and the boundary of the claimed design that forms no part thereof.

1 Claim, 1 Drawing Sheet(56)
